UNITED STATES PATENT OFFICE.

ARTHUR G. HATCH, OF DULUTH, MINNESOTA.

BUILDING BLOCK.

1,408,733.

Specification of Letters Patent.

Patented Mar. 7, 1922.

Application filed January 14, 1921. Serial No. 437,272.

To all whom it may concern:

Be it known that I, ARTHUR G. HATCH, a citizen of the United States, residing at Duluth, in the county of St. Louis and State 5 of Minnesota, have invented certain new and useful Improvements in Building Blocks, of which the following is a specification.

This invention relates to a new and improved building block, and more specifically to a block of special form adapted to give a maximum of strength with a minimum of material.

This block is particularly adapted for concrete construction. As is well known, concrete and similar block materials have an excess of crushing strength over that required in general building construction. The limiting feature in the thickness of concrete walls ordinarily consists in the necessity for lateral stability, rather than in the ability to carry the necessary load. It is therefore highly desirable, from the standpoint of the economical use of the material, 20 that the wall be provided with proper intermediate spaces, rather than being solid. Moreover, a hollow wall has great advantages, in that the air space acts as a non-conductor of heat, and also tends to prevent 25 passage of moisture inwardly through the wall. Since the walls vary in height, it is highly desirable that standard blocks for wall construction be adapted for use in walls of varying thickness, in order that the thickness 30 may be commensurate with the lateral stability necessary for the height.

It is an object of the present invention to provide a building block which may be readily cast of concrete or similar material, 40 and which affords a maximum of strength with a minimum volume of material.

It is a further object of the invention to provide a block which is particularly suitable for casting in large quantities, and 45 which is readily removable from the form. It is an additional object to provide a block which is adapted for use in walls of varying thickness. Other and further objects will appear as the description proceeds.

50 I have illustrated a preferred form of my invention in the accompanying drawings, in which—

Figure 1 is a face view of the block, the interior construction being indicated in dotted lines;

Figure 2 is a top view of the block;

Figure 3 is a rear view of the block;

Figure 4 is a section taken on line 4—4 of Figure 3; and,

Figure 5 is a section taken on line 5—5 60 of Figure 3.

The block may be said to consist of a substantially flat face portion 6, having end flanges 7, and upper and lower flanges 8, and having the transverse wall 9 joining the upper and lower flanges, the transverse wall being of less height than the side flanges. The peripheral flanges form a continuous peripheral wall of uniform height. The end flanges 7, as shown, have an arcuate inner 70 surface 7'. The center of curvature of this arc lies substantially at the point 10 in Figure 4; or, in other words, at substantially the junction of the plane face and the peripheral edge. This form of inner face renders the end flange 7 quite heavy, and adapted to take considerable compression load. This form of flange also has an important advantage in assisting the ready removal of the block from the mold, as is more 80 fully described in my copending application Serial No. 437,273, filed on even date here-with.

As best shown in Figure 5, the upper and lower walls 8 have flat inner faces and are 85 thickest at their point of junction with the plane face portion of the block. When the block is placed in the wall, these flanges 8 act substantially as cantilevers, transmitting the load which they receive to the plane face 90 portion of the block. The transverse wall 9 joining the two flanges 8 aids materially in supporting the block, and the flange, as well as its cantilever action, acts as a beam between the end flanges 7 and the transverse 95 wall 9. The length of the span of these side flanges is so short, the flanges are so thick, and the loads received relatively so small, that the material may readily take care of any small tensile stresses involved.

100 As described in my copending application Serial No. 437,274, filed on even date here-with, this form of block is particularly susceptible of use in walls of varying thickness, it being possible to use one row of 105 blocks with flat slabs against the rear faces, or to use two rows of blocks with their inner faces toward each other. Various other combinations affording thicker walls may be also used.

110 I provide grooves 11 which extend around the peripheral wall of the block. These

grooves, as shown, are semi-circular in cross section and extend parallel to the plane face of the block. These grooves may simply aid in bonding the blocks to the mortar which is to be placed between adjacent blocks, or they may serve to form between co-acting blocks convenient channels for placing reinforcing bars or members adapted to give the completed wall additional lateral or vertical strength, particularly as regards tensile stresses.

The block as shown is extremely simple in design, is very efficient as regards its utilization of the strength of the material, and affords a very great saving in material over a solid block of the same external dimensions. As has been pointed out, the strength of this block is adequate for all normal uses and its lateral stability is much greater than that of a solid block comprising the same amount of concrete. Moreover, the use of lighter blocks renders the entire wall much lighter and hence reduces the load which need be carried by the lower courses of block.

This form of block is adapted to be removed from its mold by lifting one end, the other end rotating about the center of curvature of the arcuate inner surface of the end flange. In order that this rotation may take place without disturbance of the adjacent block or of the end of the mold, this arc should have its center of curvature in or above the upper surface of the block. It should not be beyond or below the block surface since in that case rotation of the block would carry portions thereof outside of the space the block occupies when flat in

the mold. This is to be avoided in order not to disturb an adjacent block or to injure block corners against the mold end.

While I have referred to the face of the block as being substantially flat, it is to be understood that it may be formed in any desired design or surface without in any way modifying the utility or function of my particular block structure.

I claim:

1. A building block having a substantially plane face, the opposite face carrying flanges having their outer faces formed upon a smooth convex curve, the locus of the center of curvature being an area comprising and bounded by the substantially plane face and a plane erected perpendicular thereto at the adjacent edge of the block.

2. A building block having a substantially plane face, the opposite face carrying convex cylindric flanges adjacent opposite edges of the block, the axis of the cylindric of the flanges being parallel to the plane face and parallel to the adjacent edge of the block.

3. A building block having a substantially plane face, the opposite face carrying a peripheral wall, the inner surface of the portions of the peripheral wall adjacent opposite edges of the block being formed upon the arc of a circle, the center of curvature being located approximately at the adjacent peripheral edge of the plane face of the block.

Signed at Duluth, Minnesota, this 6th day of January, 1921.

ARTHUR G. HATCH.
